(57) **CLAIM**

The ornamental design for a display screen or portion thereof with graphical user interface, as shown and described.

DESCRIPTION

FIG. 1 is a front view of a display screen or portion thereof with graphical user interface; and, FIG. 2 is a front view of another embodiment of the display screen or portion thereof with graphical user interface. The outermost broken lines in FIGS. 1-2 illustrate a display screen or portion thereof and form no part of the claimed design. The remaining broken lines illustrate portions of the graphical user interface and form no part of the claimed design.

1 Claim, 2 Drawing Sheets

FIG. 1

FIG. 2
